FIG. 1.

FIG. 2.

FIG. 3.

FIG. 4.

FIG. 1 is a perspective view looking from the front and to the right of a desk embodying the present invention;

FIG. 2 is a perspective view looking from behind the desk; and

FIG. 3 is a perspective view looking from behind the desk from another vantage point.

FIG. 4 is an enlarged fragmentary plan view of the desk top wherein portions thereof have been omitted for convenience of illustration and wherein the relative placement of the spacer strips is shown in greater detail.

The design is characterized by the use of horizontal spacer strips positioned between the uppermost substantially co-planar horizontal surfaces of the desk top and each of the desk side supports, all as shown.

I claim:

The ornamental design for a desk, substantially as shown and described.
